ACTUATING AND LOCKING MECHANISM
FOR GRIPPING DEVICES

Herbert C. Otis, Dallas, Tex.

Application April 25, 1938, Serial No. 204,252

10 Claims. (Cl. 24—249)

This invention relates to new and useful improvements in actuating and locking mechanism for gripping devices.

One object of the invention is to provide an improved actuator which is particularly adapted for use in operating the gripping elements of a well snubber, of the type set forth in my Letters Patent No. Re. 19,498, issued March 12, 1935.

In running pipe, or tubing, into the well bore under pressure, it is necessary to force, or pull, the pipe downwardly into the hole and to accomplish this, equipment, generally referred to as snubbing equipment, is employed. The snubbing equipment usually consists of a travelling snubber, which grips the pipe and pulls the same downwardly into the bore against the closed well pressure, and a stationary snubber, which is employed to grip the pipe and prevent it from being blown from the well by the well pressure while the travelling snubber is being raised to take a new grip on the pipe. In other words, the travelling snubber grips the pipe and is moved downwardly to force the pipe into the well bore and during this time, the stationary snubber is inactive. When the travelling snubber reaches its limit of downward movement, the stationary snubber is engaged with the pipe to hold the same until the travelling snubber has been moved upwardly to take a new grip on the pipe. After the travelling snubber has again been engaged with the pipe, the stationary snubber is released and the operation repeated.

The usual stationary snubber employs pivoted gripping dogs which are adapted to be moved into gripping engagement with the pipe by means of a handle or operating member, which is relatively short in length. The dogs must be held in engagement with the pipe while the travelling snubber is moved to a new position and this is usually done by one man who holds the handle in a proper position to maintain such gripping engagement. Since the handle, which operates the gripping dogs, is relatively short, a relatively small leverage is had, which makes it difficult to exert sufficient force on the dogs to move them into tight gripping engagement with the pipe.

It is, therefore, one of the objects of this invention to provide an auxiliary operating means for actuating the gripping elements of well snubbers, or other gripping devices, whereby operation of said device is made easier and may be accomplished more rapidly.

An important object of the invention is to provide an improved operating mechanism for the gripping dogs of well snubbers which is constructed so that the force exerted is amplified or increased, which facilitates actuation of the dogs by one operator, and which is provided with latching means for locking the mechanism in a position holding the dogs in gripping engagement

with the pipe, whereby the necessity of one person holding said dogs in such position, is obviated.

Another object of the invention is to provide an operating and locking mechanism for well snubbers, or similar gripping devices, in the form of an auxiliary handle or lever adapted to be connected with the usual operating handle of the device, such as shown in my Patent Re. 19,498; the mechanism being so constructed that it may be applied to the device without any material change in the same.

A further object of the invention is to provide an improved mechanism, of the character described, wherein an auxiliary operating lever is pivotally mounted on the stationary well snubber and is connected with the usual handle thereof in such manner that said auxiliary handle may be utilized to positively actuate the dogs of the snubbers to either engage or retract said dogs from the pipe, or other element.

Still another object of the invention is to provide an improved actuating and locking mechanism for gripping devices wherein locking means is arranged to latch the actuator against movement from a position holding the gripping device in a gripping position; said means being so constructed that, when in latching position, it will not interfere with movement of the actuator in a direction increasing the gripping engagement of the gripping device.

A particular object of the invention is to provide an improved actuating and locking mechanism for a movable gripping element which is adapted to engage a pipe to hold the same against upward movement; said mechanism being so connected with the gripping element that said element may undergo a limited inward movement with relation to the mechanism when the latter is in a locked position, holding the element in gripping engagement with the pipe, whereby any tendency of the pipe to move upwardly with relation to the element will effect a tighter engagement of the element therewith.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is a side elevation of a stationary snubber equipped with an auxiliary operating and locking means, constructed in accordance with the invention and applied to a well snubber,

Figure 2 is a plan view thereof,

Figure 3 is an end elevation of the same,

Figure 4 is a partial longitudinal, sectional view taken on the line 4—4 of Figure 2;

Figure 5 is a longitudinal, sectional view, taken on the line 5—5 of Figure 1, and showing the dogs in a released position.

Figure 6 is a transverse, vertical, sectional view taken on the line 6—6 of Figure 2, and showing the latch in an engaged position.

Figure 7 is a similar view with the latch retracted,

Figure 8 is a horizontal, cross-sectional view taken on the line 8—8 of Figure 6,

Figure 9 is an isometric view of the auxiliary operating member or handle,

Figure 10 is an isometric view of the wrist pin,

Figure 11 is an isometric view of the well snubber handle,

Figure 12 is a partial side elevation of a modified form of the invention, and

Figure 13 is a partial longitudinal, sectional view taken through the auxiliary operating lever of the modified form.

The invention is hereinafter described as applied to a well snubber of the usual construction, such as is shown in my Letters Patent Re. 19,498, but it is specifically pointed out that it may be employed to operate any gripping device wherein the gripping elements are actuated by an extended handle.

In the drawings, the numeral 10 designates the usual side plates of a stationary well snubber, which are spaced from each other by spacer bolts 11. The plates are spaced sufficiently far apart to permit the elongate pipe, tubing or other element, A to extend therebetween. Gripping dogs 12 are mounted between the plates at the central portion thereof and the inner arcuate faces of said dogs receive arcuate, gripping inserts 13, which inserts are formed with gripping teeth 14. The arcuate inserts coact with each other to engage the pipe A, as is clearly shown in Figures 2 and 5.

Each dog is formed with a vertical rib 15 on its outer end and this rib is disposed between ears, or lugs, 16, which are provided on the inner end of an operating lever or handle 17. A transverse pin 18 extends through the ears and also through a slot 19 in the rib, whereby the inner end of the lever, or handle, is pivotally connected to the dog. It is noted that the slot 19 is inclined inwardly at its upper end, which permits the dogs to undergo a limited inward and upward movement with relation to the handles, as will be explained.

Each handle 17 is keyed, or otherwise secured, on a transverse shaft 20, which has its ends journaled in the side plates 10. The outer ends of each shaft project through the side plates and one of said ends receives a nut 20', while the opposite end is fastened to one end of a link 21 (Figures 1 and 2). When the handles are swung, the shafts 20 are rotated to swing the links. The inner ends of the links are connected to each other by a pin 22 which extends outwardly from one link and engages within a slot 23 in the other link, and said links form a connection between the levers or handles 17 to assure said handles swinging simultaneously, with a resultant simultaneous movement of the gripping dogs 12 pivoted thereto. With such arrangement, it is only necessary to swing one handle and the other handle will be swung therewith due to the link connection therebetween.

The outer ends of the handles 17 project from between the side plates 10 and when said handles are in the position shown in Figure 5, with said outer ends raised, the dogs 12 are retracted

so that the teeth 14 of the inserts 13 are disengaged from the pipe A. Downward swinging of the outer ends of the handles moves the dogs 12 toward each other, whereby the teeth 14 engage the pipe and so long as said handles are lowered (Figure 4) the pipe is gripped or engaged by the dogs.

The above construction, except for the slot 19, which could be omitted, is that of one type of the usual well snubbers now in general use, and forms no part of the present invention, having been described merely for the sake of clarity. The snubber may be supported in any suitable manner but is shown as resting on a supporting plate 24 which is attached to the upper end of the well casing. The side plates 10 of the snubber are tied down or attached to the supporting plates by tie-down bolts 25 and the pipe A passing through the snubber between the gripping dogs 12 extends downwardly into the well casing.

As has been pointed out, the relative short length of the handle 17 provides a relatively small leverage, which makes it difficult to exert sufficient force on the dogs to move them into a tight gripping engagement with the pipe or to cause them to "bite" into the surface of said pipe. This is particularly true if the teeth of the dogs are worn or the surface of the pipe is extremely hard. Also, with the usual handle, after the dogs have been moved to gripping position, they must be manually held in such position by the operator holding the handle 17 down by exerting a force thereagainst.

To amplify or increase the force exerted and to increase the leverage of the handle 17, to facilitate the swinging of said handle 17, whereby the gripping dogs 12 are moved into or out of engagement with the pipe A, an auxiliary lever or actuator 30 is provided. This lever includes a body portion or block 31 which has a general square shape in cross-section (Figure 9) and an extension bar 32 is preferably made integral with the body, extending outwardly from one end thereof. The bar is of a greater height than the body, whereby its upper longitudinal edge 45 is in a plane above the top of the body and a portion of said bar overlies the block. The upper portion of the bar is formed with an elongate, longitudinal slot 33.

The body or block 31 is disposed between a pair of extension plates 34, recessed or mortised so as to fit against the inner faces and ends of the side plates 10, as is best shown in Figs. 2 and 3, and are secured to the inner faces of said side plates. These extension plates are bolted to said side plates by the spacer bolts 11, and are thus rigidly held in place in parallel relation to each other, at the lower portion of the snubber. The extension plates form a rigid yoke for receiving the actuator or lever 30. The lever is pivoted between the projecting ends of the plates 34 on a transverse bolt 35 which passes through the outer portions of the plates and also through an opening 36 formed in the block 31 of the lever. The opening 36 is located near the outer end of the block or body 30, whereby the greater portion of said block is disposed between the plates 34 inside of the pivot bolt 35, as is best shown in Fig. 4. The outer end of the bar 32 of the lever projects outwardly from between the plates 34 and a suitable rod or handle 37, which may be readily grasped by the operator, has one end fastened thereto. The rod 37 may be of any desired length and, manifestly, when the operator swings the rod, the lever 30, to

which it is attached, is swung on the pivot bolt 35.

For connecting the usual operating handle 17 of the snubber with the auxiliary actuator or lever 30, the outer end of said handle is formed 5 with a groove or recess 38 in its top (Fig. 11). The groove is located near the outer end of the handle and is adapted to receive a wrist pin 39 which may rotate therein. The wrist pin is formed with a pair of transverse openings 40 (Figure 10) which are spaced from each other. The outer end of the handle 17 has vertical slots 42 (Figure 11) which slots are located in alignment with the openings 40 in the pin 39.

A U-bolt or yoke 43 is confined within the 15 longitudinal slot 33 of the auxiliary actuator or lever 30 and has its arms 43' extending upwardly within the vertical slots 42 in the handle 17 (Figs. 3, 4 and 5). The threaded extremities of the arms of said U-bolt pass through the openings 20 40 in the wrist pin and receive lock nuts 44, whereby the U-bolt is fastened to the wrist pin 39 and auxiliary lever 30 so as to connect the same. By adjusting the lock nuts 44, the distance 25 between the pin 39 and lever 30 may be varied, whereby an adjustment is provided to compensate for variation in pipe diameters, irregularity or wear in the pipe surface, or teeth of the gripping dogs, etc.

In operation, assuming that the gripping dogs 30 are in a retracted position as shown in Figure 5, the outer end of the handle 17 is raised, as is the outer end of the lever or actuator 30 and rod 31. The operator merely grasps the rod and moves the same downwardly so as to swing the extension 32 of the lever downwardly. This extension has the U-bolt 43 confined within its longitudinal slot 33 and, therefore, a downward pull is exerted on the U-bolt, whereby the outer end of the handle 17 is pulled downwardly. Such downward movement of the handle 17 causes said handle to swing, rotating the shaft 20, on which it is mounted, whereby the other handle 17 is swung through the links 21 and both dogs 12 are moved into gripping engagement with the pipe A. As 45 the swinging of the lever 30 continues, the U-bolt 43 rides along the slot 33, such movement being permitted by the wrist pin which rotates in its groove 38 during this time. The swinging of the lever 30 by means of the rod 31 is relatively easy and requires little effort, due to the fact that the leverage, ordinarily obtained by the handle 17 alone, is multiplied and increased by the provision of the pivotally mounted auxiliary lever 30. When the dogs are in a gripping position, as 50 shown in Figure 4, the lever 30 and rod 31 are substantially horizontal and may be manually held in such position. The dogs 12 may undergo a limited inward and upward movement with relation to the handles 17 due to the inclined slot 19 through which the pivot pin 18 extends. The inclination of the slot 19 is such that if there is any tendency of the pipe A to move upwardly while the dogs are gripping the same, the engagement between the pipe and dogs causes the 55 dogs to move upwardly, whereby the inclined slots move said dogs into a tighter engagement with the pipe.

After the dogs 12 are engaged with the pipe, the auxiliary lever 30 may, if desired, be manually held in the position shown in Figure 4, whereby the dogs are maintained in gripping position. However, to obviate the necessity of manually holding said lever 30 and to automatically latch the same in this position, a sleeve 45 (Figures 75, 6, 7 and 8) has one end threaded into an opening

46 formed in one of the extension plates 34 between the pivot bolt 35 and the spacer bolt 11. A latching plunger 47 is slideable within the sleeve and has its inner end adapted to project beyond the inner side of the plate into the path of the 5 swinging lever 30. A coiled spring 48 is confined between the other end of the plunger and a plug 49 which is threaded into and closes the outer end of the sleeve 45 and this spring constantly urges the plunger inwardly toward the lever 30 to the position shown in Figure 6.

For limiting the movement of the plunger within the sleeve and also for retracting said plunger, as will be explained, the top of said plunger is formed with a recess 50 within which 15 a cam 51 is located. The cam is eccentrically mounted on a shaft 52 which extends upwardly through an opening 53 in the top of the sleeve. An operating arm 54 is fastened to the upper end of the shaft and by rotating said arm, the 20 cam 51 is revolved.

When the cam is in the position shown in Figure 8, the spring 49 acting against the plunger moves the end of the plunger inwardly toward the lever 30 so that the end of said plunger projects beyond the inner side of the plate 34. With the plunger in this position and with the auxiliary lever or actuator 30 in the position shown in Figure 5, the top of the block 31 of said lever is below the plunger. In this position, the gripping dogs are in a released position.

As the lever 30 is swung to move the dogs into gripping engagement with the pipe 12, as has been explained, the top of the block 31 strikes the projecting end of the plunger 47 and depresses the same under tension of the spring 48. This projecting end of the plunger may be rounded, as shown at 47', to facilitate its engagement and depression by the block. As the plunger is depressed, the block 31 moves upwardly to align a recess 55, formed in the side of said block, with said plunger, whereupon the spring 48 immediately moves the end of the plunger into said recess. The recess 55 is positioned so as to receive the plunger 47 after the dogs 12 have moved into gripping engagement with the pipe, whereby the plunger locks said lever against a return movement and thus the dogs are maintained in their engaged position. The bottom of the recess 55 is open (Figure 9) so that if it is desired to further tighten the dogs after the plunger 47 has entered the recess, this can be done. Thus, the plunger locks the lever against movement in one direction only, such movement being swinging of the inner end of the block 31 in a downward direction, which releases the dogs. In this manner, the gripping dogs 12 are maintained in gripping position so long as the plunger 47 engages within the recess 55.

When the dogs are to be released from the pipe 60 A, the operating arm 54 on the cam shaft 52 is rotated to revolve the cam 51. Rotation of the cam in a counter-clockwise direction in Figure 8, causes said cam to retract the plunger 47 under tension of the spring 48, moving said plunger to the position shown in Figure 7. Such movement of the plunger retracts the same from the recess 55 and permits swinging of the member 30 in either direction. After the plunger is retracted, the rod 31 and extension 32 are swung upwardly, 65 which moves the inner end of the block 31 downwardly. Upward swinging of the extension 32 causes the same to engage the lower end of a depending lug or abutment 56, which is secured to the outer end of the snubber handle 17 by bolts 70 75

57, and thereby move the outer end of the handle upwardly, which results in a retraction of the dogs 12 from their gripping engagement with the pipe. It is noted that, if desired, the lug 56 5 may be omitted, in which case the extension 32 would engage the underside of the handle 17 to move it upwardly. The use of the lug is preferable because the extension 32 does not have to travel as great a distance in order to release the 10 dogs 12.

In Figure 12, a modified form of the invention is shown, wherein inclined extension plates 34' are substituted for the plates 34. An auxiliary lever or actuator 30' is pivotally mounted between the plates 34' on a bolt 35'. The lever 30' includes a block 31' having a rod 37' extending outwardly therefrom and this lever is adapted to be swung in the same manner as the lever 30 in the first form. The block 30' has an upstanding hook 60 which is arranged to be engaged with the U-bolt 43, whereby said block is connected with the handle 17 of the snubber. The operation of this form of the invention is substantially the same as the first form, the auxiliary lever 20 or actuator 30' being utilized to actuate the handle 17 and move the gripping dogs. If desired, the latch, including the sleeve 45 and plunger 47, may be mounted in one of the extension plates 34' and said plunger coacts with a recess 25 (not shown) in the lever 30' to lock the lever against movement to a releasing position.

From the foregoing, it will be seen that the provision of the auxiliary lever or actuator amplifies the leverage and greatly facilitates operation of the dogs. One man may quickly and easily move said dogs into gripping engagement and after being so moved, the dogs are held in such position by the latch plunger 47 which prevents return of the auxiliary lever to its original 40 position. Thus, the dogs are automatically latched in gripping position and cannot be retracted until the plunger is manually disengaged from the recess in the auxiliary lever.

It is pointed out that although the invention 45 has been shown and described as applied to a well snubber having pivoted gripping dogs actuated by a pivoted handle, the same may be utilized to actuate any movable gripping element, or elements.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. The combination with a movable gripping device having a face for gripping an elongate member, of a support, a handle fulcrumed intermediate its end on said support and also pivoted to said gripping device, a lever pivoted on the support and having its pivot spaced further from the gripping device than the pivot of the handle, a U-bolt having its upper end mounted on the outer end of the handle and depending therefrom, the lever having a longitudinal slot therein through which the U-bolt extends, whereby said lever and handle are connected together and the lever may be utilized to swing the handle.

2. The combination with a movable gripping device having a face for gripping an elongate

member, of a support, a handle fulcrumed intermediate its end on said support and also connected to said gripping device, a lever pivoted on the support and having its pivot spaced further from the gripping device than the pivot of the handle, a U-bolt having its upper end pivotally mounted on the outer end of the handle and depending therefrom, and a hook on the lever for engaging the U-bolt to connect the handle and lever together, whereby the lever may be utilized to swing the handle.

3. In a well pipe snubbing device, the combination of a movable gripping device for engaging said pipe and a handle fulcrumed intermediate its ends for operating said gripping device which is pivoted to one end of said handle, of an actuator including a pivoted lever, a pivotal element for connecting said lever adjacent its pivot point to the handle on the opposite side of its fulcrum from its point of connection to the gripping device so as to amplify the leverage of the handle when the lever and handle are swung, and means for locking the lever when the gripping device is at one end of its movement.

4. In a well pipe snubbing device, the combination with a support operable with a pipe including a gripping device for engaging such pipe and a handle pivoted on the support and having the gripping device pivoted to its inner end, of a lever pivoted on the support below the handle and having its pivot spaced further from the gripping device than the pivot of the handle, a U-bolt having its upper end mounted on the outer end of the handle, and means for pivotally connecting the U-bolt with the lever adjacent the pivot thereof.

5. A well pipe snubbing device as set forth in claim 4 and a latch carried by the support and engaging the lever.

6. A well pipe snubbing device as set forth in claim 4 and a projection on the handle disposed to be engaged by the lever upon its upward swing to swing said handle and retract the gripping device.

7. A well pipe snubbing device as set forth in claim 4 wherein the support is provided with extension plates and the lever is pivotally on said plates.

8. A well pipe snubbing device as set forth in claim 4 and a member attached to the lever having a slot therein extending longitudinally of the lever for receiving the lower end of the U-bolt for pivoting the said bolt to the lever.

9. A well pipe snubbing device as set forth in claim 4 wherein the U-bolt is pivoted to the lever by a hook.

10. In a well snubbing device, the combination of a support open for receiving an upright well tubing, opposed gripping elements disposed in the support for engaging a pipe and holding it against longitudinal movement, a handle fulcrumed intermediate its ends on said support and connected at its inner end to one of the gripping elements, a lever pivoted on the support adjacent the handle, means connecting the lever and the handle for swinging the handle and moving the gripping element connected thereto into gripping position, and an abutment on the handle disposed to be engaged by the lever when the latter is swung in the opposite direction to swing the handle to release the gripping element.
